AERIAL BOMB

George E. Graver, San Francisco, Calif., assignor
of one-half to Willard M. Gillies, Los Angeles,
Calif.

Application November 29, 1938, Serial No. 243,019

2 Claims. (Cl. 102—2)

This invention relates to aerial bombs, and more particularly to means for detonating the same prior to striking the ground.

An object of the invention is to provide a simple, practical and efficient detonating device for aerial bombs.

Another object is to provide a detonating means for aerial bombs adapted to increase the effectiveness thereof by detonating the bombs just prior to striking the ground.

Other objects and advantages will appear and be brought out more fully in the following specification, reference being had to the accompanying drawing, wherein,

Fig. 1 is a side view partly in section of a bomb embodying my invention.

Fig. 2 is a partial view in section of the forward end of the same and showing the detonating mechanism in extended position.

Heretofore aerial bombs of a type dropped by airplanes have been detonated upon striking the ground and a large percentage of the explosive power, often as much as seventy percent, is ineffective, this energy resulting only in making a hole in the ground. Therefore, it follows that if the bomb could be exploded a second or two previous to the impact of the bomb with the ground, the explosive force thereof would have greater effectiveness than otherwise. Such a result is achieved by this invention as will be apparent from the following description.

Referring more particularly to the drawing, I show a bomb 5 of the type usually carried by airplanes and the like, having a chamber 6 for the explosive charge, and having a tapered nose or end portion 7 and a plurality of tail fins 8. A cross wall 9 forms the front end of chamber 6, and the nose 7 is provided with an open end 10.

A pair of longitudinal partitions 11 extend from the wall 9 to the open end 10 and form a chamber 12 adapted for the accommodation of a plummet 13 secured by a chain 14 to the wall 9. These partitions also form two compartments in which are arranged the batteries, as later described.

The explosive charge is adapted to be detonated by an electric current which may be supplied from one or more electric batteries 15 suitably secured to the wall 9 or otherwise. Wires 16 connect the batteries 15 to the explosive charge, and wires 17 connect the batteries 15 to a pair of contacts 18 suitably secured in the plummet 13.

A metallic rod 19 is positioned in a bore 20 in the plummet 13 and is provided with a cap 21 which closes the open end 10 of the bomb. The cap 21 is provided with a bore hole 22, and the nose 7

is provided with a tapped bore 23 adapted to receive a threaded stud 24 which passes through the hole 22 by which means the cap 21 is secured to the nose 7.

The stud 24 is formed with an air screw 25 at its outer end which will turn when the bomb is in flight and unscrew the stud 24 and release the cap 21 from the nose 7.

A lock screw 26 is positioned laterally in the plummet 13 and engages the rod 19 with sufficient pressure to keep the rod 19 separated from the contacts 18. The pressure of the screw 26, however, is such that when the plummet 13 strikes the ground, the impact of the cap 21 will cause the plummet 13 to be advanced along the rod 19 causing the latter to complete the electric circuit between the contacts 18 thus detonating the charge.

Fins 8 are each provided with a curved terminal portion 27, the function of which is to retard the bomb 5 sufficiently to permit the plummet 13 to fall out in advance of the bomb after the cap 21 has been released by the air screw 25, the plummet however being held by the chain 14 the length of which may vary from a few to several feet as may be determined upon by actual conditions. It will thus be apparent that by the foregoing construction, the bomb will be detonated a few feet before striking the ground and the full explosive power will be effective otherwise than by making a large hole in the ground.

Having described my invention what I claim is:

1. In combination, an explosive carrying aerial bomb having an elongated body, means forming a restricted chamber in the forward end thereof, a plummet stored in said chamber, a chain in said chamber and connected to the body and the plummet for limiting the distance the plummet may leave the body, means for detonating the explosive including batteries in the body on the outside of the restricted chamber, contacts in the plummet and wires connecting the contacts in a circuit including the batteries, a cap closing the end of said chamber, a sliding rod in the plummet connected to said cap for closing the said contacts, and an air propeller operated screw securing said cap to the body, whereby the cap and plummet are released after a predetermined time of travel of the bomb.

2. In combination, an explosive carrying aerial bomb having an elongated body, means forming a restricted chamber in the forward end thereof, a plummet stored in said chamber, means in the body including batteries, contacts in said plummet

met, and cables stored in the restricted chamber connected in circuit with the batteries, contacts and explosive charge for detonating the same, a rod passing through the plummet and normally held out of contact with the contacts, and an enlarged head carried by the outer end of the rod and closing the end of the restricted chamber and extending beyond the periphery thereof, and

an air propeller having a screw threaded shaft passing through the edge of the enlarged head and into the body of the bomb for securing the same to the body, whereby the cap and the plummet are released after a predetermined time of travel of the bomb.

GEO. E. GRUVER.
